APPARATUS FOR AUTOMATICALLY TUNING
RADIO RECEIVERSEdgar M. Butler, Brooklyn, N. Y., assignor of
fifty per cent to Anders Jordahl, New York,
N. Y.

Application October 18, 1928, Serial No. 313,201

21 Claims. (Cl. 250—40)

This invention relates to apparatus for automatically tuning radio receivers.

The invention has for its object the automatic tuning-in of any one of a plurality of predetermined broadcasting or transmitting stations, as well as stations intermediate thereof, by the simple expedient of merely pressing a button or the like located on the apparatus itself and/or at a point remote therefrom.

10 The invention comprises, broadly any means and preferably as disclosed and described electrically and/or electromagnetically operated means for automatically, quantitatively and selectively rotating, and, when the station desired 15 is tuned-in, automatically discontinuing rotation of, the shaft of the gang condenser, or other tuning elements, of so-called one-dial receivers, as, for instance, in inductive tuning, where rotatable contactors are caused to tap any one of a plurality of tapped sections of the radio frequency 20 transformers.

The apparatus is provided with a plurality of push-buttons or the like, each adapted to tune-in a different station, frequency or wavelength. 25 There is associated with each button an element or elements which may be adjusted to bring in any predetermined signal, so that when said button has been operated it will bring in the station for which the element has been set.

30 The apparatus is also provided with buttons which are operated to bring in stations intermediate those for which adjustment has been made as well as the predetermined stations.

There is provided also a remote control which 35 is connected to the apparatus by a connector plug and cord. Said remote control has the same number and arrangement of buttons as are located on the apparatus, and, in addition, is provided with other elements, such as a volume control, off-and-on switch, wavemeter or station indicator, and the like.

In the accompanying drawings there are illustrated practical embodiments of my invention, but it is clear that the apparatus is susceptible 45 of other mechanical and electrical embodiments and modifications which do not depart from the scope and principle thereof.

Fig. 1 is a front elevation of a practical embodiment of my invention;

40 Fig. 2 is a side view on the line 2—2 of Fig. 1; Fig. 3 is a side view on the line 3—3 of Fig. 1;

Fig. 4 is a circuit diagram of the apparatus illustrated in Fig. 1; together with a circuit diagram of the remote control;

45 Fig. 5 is a circuit diagram of a modified form

of said apparatus; 5a and 5b are sequence views;

Fig. 6 is a schematic representation showing the position of cams and switches at zero setting of the dial, rotation being counterclockwise;

Fig. 7 is a schematic representation showing the subsequent position of said cams when the apparatus is tuned to a predetermined station;

5 Figs. 8, 9 and 10 are, respectively, top, bottom and cross-sectional views of one embodiment of remote control box;

10 Fig. 11 is a top view of another form of remote control box.

The apparatus is provided (Figs. 1, 2 and 3) with a reversible motor M having a shaft a which fits into a sleeve b. Passing through said sleeve b and shaft a is a pin c. Passing also into said sleeve b is one end of a camshaft d, the other end passing through an ear e of the standard f. The sleeve b passes through the ear g of the standard h. Mounted on the inner end of sleeve 20 b is the pin disc i of clutch j, provided with a pin k which engages an aperture in convex spring disc l clamped between pin disc i and disc ii, the latter being mounted on a bearing n having a keyway o which rides on a key p projecting from 25 the camshaft. The pressure of the spring disc l against disc ii is regulated by locking nut q threaded on said camshaft. Assembled on the camshaft are a plurality of cams A, B, C, etc., which are adjusted as described hereafter and 30 fixed in adjusted position by set screws y, y. The cams are locked together in adjusted position by locking nuts r and s. A bracket t is mounted on the standards f, h, to which are attached switches SA, SB, etc. The camshaft d 35 and condenser shaft u of the receiver are connected in a bearing v in the tuning dial w of the receiver.

40 Referring to clutch j, enough pressure is put on the spring disc so as to make the camshaft rotate with the motor when the latter is in operation; but the pressure of the spring disc against the pin disc is not great enough to cause the motor to rotate with the camshaft when the dial w is manually rotated; in other words, the 45 resistance of the motor to manual rotation is greater than the resistance between the spring disc and pin disc, so that when the camshaft is manually rotated, it will rotate independently of the motor, thereby permitting manual tuning 50 of the receiver.

55 Cooperating stops z, z', are provided on the camshaft and standard f to limit the rotation of the camshaft through a predetermined arc of approximately 180 degrees.

The principle underlying the invention will best be understood by referring to Figs. 6 and 7, which illustrate, in a schematic and graphic way, the manner in which the elements, which determine 5 and control the extent and direction of rotation of the motor, operate.

The apparatus is provided with a plurality of cams, A, B, C, D, E, etc., which are mounted on a shaft connected to the motor and to the gang 10 condensers of the receiver, in the manner shown in Figs. 1 and 2.

The cams are first assembled haphazardly on the shaft, a cam being provided for each station to be automatically tuned in. The camshaft, 15 having been connected to the shaft of the receiver, the dial of the receiver is rotated until one extremity of its excursion is reached, say at zero graduation. The dial is then rotated until the first station, for which it is desired to provide 20 an automatic stop, is tuned-in. Cam A is then rotated or adjusted on its shaft so that the undercut section X of the cam, which will, for convenience, be called the point of neutrality or inoperativeness, pushes the movable contact SA2 25 of switch SA into a position where it is making contact with neither stationary contact SA1 nor SA3; in other words, both circuits connected to switch SA are open, so that the motor can rotate in neither direction. When this adjustment 30 of cam A has been made, it is immovably secured to the camshaft by a set screw or other means.

The dial of the receiver is then rotated until the second station, for which it is desired to create an automatic stop, is tuned-in. Cam B 35 is then adjusted in the same manner as cam A with respect to the movable contact SB2 of switch SB, namely, with the portion X of the cam B pushing the movable contact into a position of neutrality. In the same manner are the other 40 cams adjusted and secured in place.

Now, when the dial of the receiver has been returned to zero it will be found that the adjusted cams have the relative positions shown in Fig. 6, and all the movable contacts of switches SA, etc., 45 make contact with the stationary contacts SA3, etc.

Now it happens that when SA2—SA3, SB2—SB3, etc., are closed, it permits, when their respective circuits are energized, the motor to 50 operate in a counterclockwise direction, and the cams will rotate with the motor until the switch made operative, as described hereafter, is made inoperative by the cam associated with it, namely, when the movable contact of the switch reaches 55 X of the cam. Since the point at which this takes place happens to be the point where a station has been tuned in originally, this station will be tuned in again automatically.

Fig. 7 shows this state of affairs. In this instance, station C has been tuned-in for by depressing the proper button. The motor has rotated in a counterclockwise direction, because SC2—SC3 was closed when the circuit thereto was energized. Cam C has rotated with the motor until X of the cam pushed the movable contact of the switch SC into neutral. At this point the motor is automatically stopped, and the station tuned for has been brought in.

However, the other cams have been rotated 70 a like amount with cam C so that at the point where station C is tuned-in, or, what is the same thing, the switch SC is in neutral, the cams have the positions shown in Fig. 7.

While cam C was rotating, cams A and B rotated beyond the point of neutrality with respect 75

to the movable contacts of their associated switches, and pushed said contacts from stationary contacts SA3, SB3, to contacts SA1 and SB1, respectively, closing the circuits to the motor permitting it, when said circuits are energized, to rotate in a clockwise direction. And since, in order to get back to the point of neutrality of cams A and B, or, what is the same thing, tune-in stations A or B, it is necessary to rotate the cams in a clockwise direction, the switches 10 are automatically set by said cams for such rotation. So that by energizing switches SA or SB, the motor and cams will rotate in a clockwise direction until cam A or cam B releases its pressure against the movable contacts and permits 15 them to assume a neutral position, automatically stopping rotation of the motor.

It will be observed that in tuning for station C the cams D and E have not been rotated sufficiently to affect the position of the movable contacts SD2, SE2; in other words, the original setting of switches SD and SE has not been altered. Energizing the circuits to either of said switches will cause the motor to rotate in a counterclockwise direction until the cam D or E, as the case 20 may be, pushes the movable contact into a neutral position.

Assuming station E to be tuned-in, then the cams A, B, C and D will bear against the movable contacts SA2, SB2, etc., to close circuits to said 30 switches permitting the motor to rotate in a clockwise direction when any of said circuits is energized.

Referring to Fig. 4, we have a circuit diagram of the apparatus shown in Fig. 1, and employing the principles illustrated by the schematic Figures 6 and 7.

Current for operating the motor M is taken from any suitable source 1. It is assumed, in this instance, that the voltage of the source is high, say 110 volts. In order to obviate the use of this high voltage in the push-button circuits, where it may shock the operator, there is provided a step-down transformer 2 for stepping down the voltage to said button circuits. The primary 3 of said transformer is connected at one end to the source 1, and the other end of said primary is connected through a switch 6 to the other line of said source. The secondary 4 is connected to what may be generally referred to as the push-button circuit. The conductor 5 connecting one end of the primary to one of the terminals of the source 1 is provided with a switch 6 for turning the current to the apparatus off and on, and a similar switch 7, mounted on a remote control box, hereafter described, is also connected in series with said conductor.

A conductor 8 connects field coil MF2 of the motor M to one side of source 1 and a conductor 9 connects the other side to stationary contacts 10 and 11 of switches 12 and 13 of the multiple relay switches RS1 and RS2. The movable contact 14 of switch 12 is in turn connected by another conductor 15 to one of the brushes MB2 of the motor. The movable contact 16 of switch 13 is connected by conductor 17 to the brush MB1 of the motor. Connected also to the brush MB2 by conductor 15 is the stationary contact 18 of the switch 19 of RS2. The movable contact 20 of switch 19 is connected to the field coil MF1 of the motor by conductor 21. The stationary contact 22 of the switch 23 of relay switch RS1 is connected to brush MB1 of the motor by conductor 17, and the movable contact 24 of said 70

switch is connected to field coil MF1 by conductor 21.

The switch 12 of relay switch RS1 is adapted to open and close the circuit MB2—MF2 of the motor; switch 13 of RS2, MB1—MF1; switch 23 of RS1, MF1—MB1, and switch 19 of RS2, MF1—MB2 thereof.

Relay switch RS1 is provided with a further switch 25, the stationary contact 26 of which 10 is connected by conductor 27 to one terminal of an electromagnet 28, the other terminal thereof being connected by conductor 29 to the terminal 4a of secondary 4 of the step-down transformer.

The movable contact 30 of switch 25 is connected to the stationary contacts SB3, SC3, SD3 15 of the cam-actuated make and break switches SB, SC and SD, by a common conductor 31. The stationary contact 32 of switch 33 of RS2 is connected by common conductor 34 to the stationary contacts SB1, SC1, SD1 of switches SB, SC, 20 SD, and movable contact 35 of switch 33 is connected by conductor 36 to one terminal of electromagnet 37, the other terminal being connected by conductor 38 to conductor 29 to terminal 4a.

Common conductor 31 is connected by conductor 39 to a common conductor 40 which in turn is connected to stationary contacts 41 and 42 of selector switches 43 and 44, respectively, one on the apparatus and the other on the remote control box; and common conductor 34 is connected by conductor 45 to common conductor 46 connecting the stationary contacts 47 and 48 of selector switches 49 and 50 respectively, the former being located on the remote control box.

The movable contacts 51, 52, 53 and 54 of switches 49, 43, 50 and 44 respectively are connected by common conductor 55 leading from the terminal 4b of the secondary. Also connected to said common conductor 55 are the stationary contacts 56, 57, 58, 59, 60 and 61 of locking switches 62, 63, 64, 65, 66 and 67 respectively, the first three being located on the remote control box and the latter three on the apparatus.

The movable contacts 68 and 69 of switches 62 and 65 respectively are connected by common conductor 70 to movable contact SB2 of switch SB. Movable contacts 71 and 72 of switches 63 and 66 respectively are connected by common conductor 73 to the movable contact SC2 of switch SC, and movable contacts 74 and 75 of switches 64 and 67 respectively are connected by common conductor 76 to movable contact SD2 of switch SD.

The circuit shown in Fig. 4 is provided with three automatic circuits for the purpose of illustration, but the apparatus may be provided with any number of such circuits.

Beside the aforesaid automatic circuits, there are provided two additional circuits, one for producing clockwise and the other counterclockwise rotation of the motor, but these circuits are not automatic. They are intended to be used when a station for which no automatic stop has been provided is desired to be tuned in. Push button 77 controls the clockwise rotation, while 78 controls the counterclockwise rotation of the motor. Buttons 71 and 78 are not self-locking as are the automatic buttons.

When button 77 is depressed, it will close the switch 50 and energize electromagnet 37, the circuit being: beginning with the stationary contact 48 of switch 50, conductors 45 and 34, switch 33, conductor 36, electromagnet 37, conductors 38 and 29, secondary 4, common conductor 55,

and movable contact 53 of switch 50. When the electromagnet is energized it attracts the bell crank armature 79 which pushes the movable contacts 14, 24 and 30 of switches 12, 23 and 25 respectively so as to close switches 12 and 23 and open switch 25. When the switch 12 is closed current is delivered from the source to MB2—MF2 of the motor which causes the motor to rotate in a clockwise direction. It will be shown hereafter that when the corresponding switch 13 of relay switch RS2 is closed the motor will rotate in a reverse or counterclockwise direction.

When button 78 is depressed it closes switch 44 and energizes electromagnet 28, the circuit being: beginning with stationary contact 42, conductors 40 and 39, switch 25, conductor 27, electromagnet 28, conductor 29, secondary 4, common conductor 55 and stationary contact 54 of switch 44. When electromagnet 28 is energized it attracts bell crank armature 80, which in turn pushes the movable contacts 16, 20 and 35 so as to close switches 13 and 19 and open switch 33 of relay switch RS2. It has been pointed out that when switch 13 is closed the motor will rotate in a counterclockwise direction; this is so because the current source is connected across MB1—MF2 of the motor; in other words, current passes through the motor in a direction the reverse of MB2—MF2.

It will be understood that when button 77 or 78 is depressed the motor will stop only when said buttons are released by the operator; that is, the motor does not stop at any predetermined point independently (automatically) of the will 35 of the operator. For such automatic action there are provided other buttons and elements to be hereafter described.

It will be observed from a digestion of the foregoing description that the apparatus is provided with two electromagnetically operated relays which control the direction of rotation of the motor, one RS1 for clockwise and the other RS2 for counterclockwise rotation thereof.

In expanding the apparatus for automatic operation, there is connected in parallel with the relay circuits, or, what amounts to the same thing, in parallel with both selector circuits, two-circuit switches SB, SC, etc., actuated by cams B, C, D (Fig. 4), as the case may be, to operate 45 relay switch RS1 to cause clockwise rotation of the motor, which is the condition of switch SB, or to operate relay switch RS2 to cause counterclockwise rotation of the motor, which is the condition of SD. In addition, the switches SB, SC, 50 etc., are capable of assuming a position where the circuits to both relays RS1 and RS2 are kept open, which happens to be the condition of switch C.

At this point it may crystallize the understanding of the invention by indicating that the cam switch is a combination of the manually operated selector switches 50 and 44, and that for the hand of the operator there is partially substituted a cam. Thus each combination of cam and switch is, in a manner of speaking, the partial equivalent of the hand of the operator and switches 50 and 44.

The operation, circuits and elements of the automatic system are as follows: for each automatic station there is provided a push-button 81 which is locked, when depressed, in the manner hereinafter described. When the push button of switch 65, for instance, is depressed, it closes the switch and operates the relay switch RS1 for 70

clockwise rotation of the motor, the circuit being: starting with the movable contact 69 of switch 65, common conductor 70, movable contact SB2 and stationary contact SB1 of switch 5 SB, common conductor 34, switch 33, conductor 36, electromagnet 37, conductors 38 and 29, secondary 4, common conductor 55 to stationary contact 53 of switch 65; in other words the effect of depressing the button of switch 65 is 10 the same as though button 77 were depressed. This will be clear when it is observed that both switches 65 and 50 are connected across common conductors 34—55 in parallel. It will be observed also that what ultimately determines 15 which relay shall be operated is the position of the cam with respect to its coating switch. If the movable contact is on the greater curvature of the cam, as is the case in SB, it will close the switch which operates relay RS1 for 20 clockwise rotation; if the movable contact is on X of the cam it leaves the switch open, as is the case in SC, then neither relay will be operated. If on the other hand the movable contact is along the lesser curvature, as is the case in SD, 25 the switch operating relay RS2 for counterclockwise rotation will be closed.

Referring to the automatic circuit for station D: when button 81 is depressed it closes switch 67 and operates relay RS2, the circuit being: 30 beginning with the movable contact 75 of switch 67, conductor 76, SD2—SD3 of switch SD, conductor 27, electromagnet 28, conductor 29, secondary 4, common conductor 55 and stationary contact 61 of switch 67. As has been explained, 35 when electromagnet 28 is energized it operates relay RS2 to cause counterclockwise rotation of the motor. In other words, the effect of depressing the button of switch 67 is the same as if button 78 were depressed. This will be clear 40 when it is pointed out that both switches 67 and 44 are connected in parallel across common conductors 27—55.

The remote control box is provided with automatic buttons 81 and switches 62, 63, 64, the 45 latter of which are connected in parallel with switches 65, 66, 67, of the apparatus. The effect of closing any of the switches 62, 63, 64, is the same as if the corresponding switch 65, 66, 67 were closed. The remote control box is also 50 provided with selector buttons 71a, 72a and selector switches 49, 43, the latter being respectively connected in parallel with selector switches 50, 44 of the apparatus. The effect of closing switch 49 or 43 is the same as if the corresponding switch 50 or 44 were closed.

The remote control is also provided with an off and on switch 7, a volume control 82, and a station indicator 83, which may be of the meter or other type.

60 Should it not be undesirable or inconvenient to use the high voltage of house current mains, the electromagnets may be dispensed with, in which event the circuit shown in Fig. 5 may be used.

65 As in the previous instance, field coil MF2 of the motor is connected by conductor 101 to one line of the current source 102. Connected to the other line is an off and on switch 6. Brush MB2 of the motor is connected by common conductor 104 to common conductor 105 to movable contact 106 of switch 107 of selector switch SS1 and fixed contact 108 of switch 109 of automatic switch AS; also to common conductor 110 to movable contact 111 of switch 112 of selector

switch SS2 and stationary contact 113 of switch 114 of automatic switch AS.

Brush MB1 is connected by conductor 115 to common conductor 116 to stationary contact 117 of switch 118 of selector switch SS1 and to movable contact 119 of switch 120 of automatic switch AS; also to common conductor 121 to movable contact 122 of switch 123 of selector switch SS2 and stationary contact 124 of switch 125 of automatic switch AS.

10 Field coil MF1 is connected by common conductor 126 to common conductor 127 to movable contact 128 of switch 118 of selector switch SS1 and stationary contact 129 of switch 120 of automatic switch AS; also to common conductor 130 to stationary contact 131 of switch 112 of selector switch SS2 and stationary contact 132 of switch 114 of automatic switch AS.

15 The other side of the source 102 is connected by common conductor 133 to stationary contact 134 of switch 123 of selector switch SS2, to stationary contact 135 of switch 107 of selector switch SS1, and to stationary contact 136 of switch 137 operated by the automatic button 138, the movable contact 143 of said switch 137 being connected by conductor 139 to movable contact 140 of switch 125 of automatic switch AS.

20 When selector button 141 is depressed, it closes both switches 107 and 118 of selector switch SS1. Switch 107 is connected across MB2—MF2 of 30 the motor and switch 118 is connected across MF1—MB1 thereof, which connections produce clockwise rotation of the motor.

25 When selector button 142 is depressed, both switches 112 and 123 of selector switch SS2 are closed. Switch 123 is connected across MB1—MF2 of the motor and switch 112 across MF1—MB2 of the motor to produce counterclockwise rotation thereof.

30 It will be observed that in the case of selector button 141 the current passes through the motor in a direction the reverse of that of button 142.

35 Referring to the automatic system of Fig. 5, there is provided a self-locking push-button 138, which, when depressed, closes switch 131, the stationary contact 136 of which leads to line by common conductor 133 and the movable contact 143 by conductor 139 to the movable contact 140 of the automatic switch AS.

40 Fig. 5 shows the automatic switch AS set for counterclockwise rotation of the motor, the switches 114 and 125 corresponding to and being connected in parallel with switches 112 and 123 respectively of the counterclockwise selector switch SS2.

45 Fig. 5a shows the automatic switch AS open or in neutral position, while Fig. 5b shows the automatic switch AS set for clockwise rotation of the motor, switches 120 and 109 thereof being closed and corresponding to and being connected in parallel with switches 118 and 107 respectively of the clockwise selector switch SS1.

50 It will be observed that the automatic switch AS combines both selector switches SS1 and SS2, and which set of switches shall be made operative, as well as both kept open, is determined by the varying position of the cam, as will be clear from a scrutiny of Figs. 5a and 5b.

55 When contact 132 is adjacent the lesser curvature of the cam, switches 125 and 114 are closed. When contact 132 is on X of the cam, it is pushed away so as to open said switches and leave switches 120 and 109 open. This is the position shown in Fig. 5a.

Should contact 132 be on the greater curvature of the cam, switches 120, 109, are closed and switches 125, 114, remain open, so that should the automatic button be depressed the 5 motor will rotate in a clockwise direction until contact 132 reaches X of the cam, when the automatic switch AS is entirely opened, as fully explained in connection with the description of Figs. 6 and 7.

10 Figs. 8, 9 and 10 are top, bottom and cross-sectional views of one form of remote control box adapted to be connected by a suitable cable or otherwise to the apparatus above described.

The remote control box 201 comprises a base 15 202 on which is mounted a cover 203 and a plate 204, the latter being attached to the base by screws 205. The cover is provided with apertures 206 through which project automatic buttons 81 and selector buttons 77, 78 (Fig. 4).

20 The cover is also apertured to permit the shaft 207 of volume control 82, which happens to be a high resistance rheostat, to project therefrom and receive a knob 209 whereby the same may be rotated. Mounted on said cover is a knob 25 210 for operating an off and on switch 7, Fig. 4.

The device for locking the push buttons 81 is well known in the art. It comprises a series 30 of levers or strips 212 fastened at one end 213 to plate 204, and the strips are clamped near said end by a bar 214 secured to the plate 204 by screws 215, 215.

The strips are twisted 216 near the other ends 35 thereof through an angle of 90 degrees so as to be insertable in the slotted lower ends 217 of push-buttons 81, 77 and 78, and said buttons are secured to said strips by pins 218.

Depending from plate 204 is a hinge 219 to 40 which is attached a locking bar 220. The locking device operates as follows: when one of the buttons 81 is depressed it pushes the strip 212 connected to it down. The end 80° of the strip is adapted to impinge against the locking bar and push it aside. When the strip has been depressed the maximum amount the locking bar 45 springs back into its original position and the free end of the strip is held beneath it. The depressed button is released upon pressing another button, whether 81, 77 or 78, because, in the case of buttons 81, when the second button is

50 depressed the free end of the strip attached thereto impinges against the locking bar and pushes it aside, permitting the first mentioned strip to spring back into place, and the second-mentioned strip will be locked under the bar.

55 Selector buttons 77, 78, release any of the depressed buttons 81 in the same manner, but they are not adapted to lock under the bar, because said buttons 77, 78, are arranged to be depressed only part of the distance of buttons 81.

60 Adjacent the aforesaid buttons are suitable indicia 221 corresponding to the stations they are adapted to tune in.

Fig. 11 shows another form of remote control box 239. This box is provided with an off and 65 on switch 7, volume control 82, automatic and selector buttons 81, 77, 78 and a meter form of station indicator 231. The meter here employed is a voltmeter, the terminals 232, 233, of which are connected respectively to one terminal 234 70 of a potentiometer 235 and the movable contactor 236 thereof. The potentiometer is insulatively mounted on the condenser shaft u (Fig. 1), and the movable contactor is adapted to travel correspondingly with the dial attached 75 to said condenser shaft, so that when the dial

is at zero, for instance, the voltmeter shall be at zero, and so on. The dial of the voltmeter is suitably calibrated to indicate the wavelength or frequency to which the receiver is tuned. The potentiometer may be connected to the six volt terminals of the power supply or to any other source.

Having described my invention, what I claim is:

1. Automatic tuning apparatus comprising reversible motor driving means, a tuning device operated thereby, adjustable elements operable therewith, and circuit making and breaking means coacting with said elements to cause said driving means to automatically rotate said elements in either one of two directions as well as to cause the automatic discontinuance of operation of said driving means at a predetermined point in the movement of said elements. 10

2. Automatic tuning apparatus comprising a reversible motive means, a tuning device connected thereto, means for energizing said motive means, adjustable selector elements operable by said motive means and circuit making and breaking means coacting with said elements to 15 permit rotation of said motive means in either one of two directions as well as to cause the automatic discontinuance of rotation of said motive means at a predetermined point in the operation of the motive means. 20

3. Automatic tuning apparatus comprising a tuning device, a reversible motor for driving the tuning device, means for energizing the motor, and station selectors operable by said motor, said 25 selectors being operable to deenergize said motor at selected positions. 30

4. Automatic tuning apparatus comprising reversible motor means, a tuning device operable thereby, means for energizing the motor means, switches controlled by said motor means, each 35 of said switches being capable of independent adjustment for a predetermined station, one switch acting to cause the motor means to rotate in a clockwise direction, one switch acting to rotate the motor means in a counterclockwise 40 direction and the other switch acting to deenergize the motor at a position according to a predetermined station. 45

5. Automatic tuning apparatus comprising reversible driving means, a tuning device operated thereby, means for energizing the driving means, station selectors operable by said driving means and independently adjustable with respect to one another and associated with means for energizing the driving means and control 50 switches for energizing the driving means to rotate it in one of two directions. 55

6. Automatic tuning apparatus comprising reversible power means, a tuning device connected thereto, means for energizing the power means, selector switches for deenergizing the power means at selected positions of the tuning devices, said switches being operable by the power means and independently adjustable relative to one another for predetermining the selected positions 65 and control switches connected to the means for energizing the power means initially. 60

7. Automatic tuning apparatus comprising a reversible driving means operated through electro-magnetically operated switches, a radio tuning device connected to the driving means, means for energizing the driving means, adjustable selector means operable by said driving means, and circuit making and breaking means coacting with said selector means to cause op- 70 75

eration of said driving means in either of two directions as determined by the position of the tuning device as well as to cause the automatic discontinuance of operation of said driving means at a point predetermined by the adjustment of the selector means and the particular circuit making means actuated.

8. Automatic tuning apparatus comprising reversibly operated driving means, adjustable elements operable therewith, circuit making and breaking means coacting with said elements to cause said driving means to automatically operate said elements a predetermined distance in one of two directions as well as to cause the automatic discontinuance of operation of said driving means at a predetermined point in the movement of one of said elements, and independent means for operating said driving means.

9. Automatic tuning apparatus comprising a reversible motive device, a tuning device operated thereby, means for energizing the motive device, adjustable selector elements movable by said motive device, circuit making and breaking means coacting with said elements to cause rotation of said motive device in a direction predetermined by the actuation of said circuit making means as well as to cause the automatic discontinuance of rotation thereof at a predetermined point in the movement of the selected element, and independent means for operating said motive device in one direction or the other.

10. Automatic tuning apparatus comprising a reversible motive device, an adjustable element of a radio apparatus operated thereby, adjustable selector elements movable by the motive device, circuit making and breaking means coacting with said elements to permit operation of said motive device in either of two directions determined by the position of the selector elements as well as to cause stopping thereof at a predetermined point in the movement of a selector element, and a plurality of station selector manuals coacting with said circuit making and breaking means for initiating energization of said motive device.

11. The combination with a tuning member of a radio receiver, of a plurality of adjustable station selective elements and reversible motive means controlled thereby to tune in any one of a group of selected stations represented by said elements.

12. The combination with an adjustable controlling element of a radio receiving system, of means connected with said element acting upon operation to move said element in either of two directions automatically determined by the position of said means to a desired position, the connection of said means with said element being adjustable whereby said desired position may be adjustably predetermined.

13. The combination, with an adjustable controlling element of a radio receiving system, and an adjusting manual for said element, of additional means including a reversible motor for adjusting said element including a member adjustable with respect to said manual and acting upon operation to move said element in either direction to a predetermined position, the direction in which said element will be moved by the operation of said means being automatically determined by the position of said member at the time of operation of said means.

14. In an automatic apparatus of the type described, the combination comprising a movable tuning element, a reversible electro-motive de-

vice connected to said element, circuits for said device for energizing it, and a plurality of means included in said circuits for energizing the circuits to operate said device in either direction to move the tuning element to a predetermined static setting depending upon which of said plurality of means is actuated.

15. In an automatic apparatus of the type described, the combination comprising a movable tuning element, a reversible electro-motive device connected to said element, circuits for said device for energizing it, a plurality of means forming part of said circuits for energizing them, and other means driven by said electro-motive device and included in said circuits for de-energizing said device when the tuning element is at the setting predetermined by the actuation of the particular means for energizing said circuits.

16. In an automatic tuning apparatus, the combination with a movable tuning element of a reversible electric motive device connected to said element and a plurality of means for energizing said motive device to operate it in either direction to cause it to move said element to a desired static setting predetermined by the actuation of the one of said plurality of means corresponding to that setting of the tuning element.

17. In an automatic tuning apparatus the combination with a movable tuning element of a reversible electric motive means connected to said element, circuits for said motive means including a plurality of control switches for operating it in either direction, and de-energizing means in said circuits and operatively driven by said motive means whereby the motive means is operated in either direction to effect a setting of said tuning element predetermined by the actuation of the control switch corresponding to that setting.

18. In an automatically adjustable apparatus of the type described, the combination comprising a movable element to be adjusted to predetermined positions and adapted to be manually adjusted to any desired position, a reversible driving means for said element to move it, continuously connected coupling means between said driving means and element whereby the element may be driven by the driving means in either direction, and means connected to said driving means for driving it in either direction to adjust said element to predetermined settings, said coupling means being inoperative to move said driving means when said element is manually adjusted.

19. The combination with the tuning element of a radio apparatus, of a plurality of adjustable station selective elements, motive means for operating said tuning element and said selective elements, a plurality of means connected to said motive means and interconnected with said selective means whereby the tuning element tunes said apparatus to a particular wave length predetermined by the actuation of the one of said plurality of means corresponding to that wave length setting, and means in said circuits by which the tuning element is adjustable to any wave length desired within its range irrespective of the selective elements.

20. In a tuning device for radio apparatus, the combination comprising an adjustable tuning element, a reversible power apparatus connected to said tuning element for driving it, selector devices driven by said power apparatus, circuits including said power apparatus and devices, said

devices acting to interrupt said circuits to stop the power apparatus at predetermined points, and a plurality of means in said circuits and connected with said devices to start said power apparatus in the proper direction depending upon the position of the selector devices, said selector devices acting to stop the motor at a point corresponding to the particular one of the plurality of means that has been actuated.

10 21. In a tuning device for radio apparatus, the combination comprising an adjustable tuning element, reversible motor means connected to said tuning element for driving it, selector devices driven by said motor means, circuits including

said motor means and devices, said devices acting to interrupt said circuits to stop the motor means at predetermined points, a plurality of means in said circuits and connected with said devices to start said motor means in the proper direction 5 depending upon the position of the selector devices, said selector devices acting to stop the motor means at a point corresponding to the particular one of the plurality of means that has been actuated, an indicating device, and means 10 connected thereto and driven by the motor means and tuning element to display at a distance the setting of the tuning element.

EDGAR M. BUTLER.
